UNITED STATES PATENT OFFICE.

MARTIN L. BEISTLE, OF INGRAM, PENNSYLVANIA.

TROLLEY.

SPECIFICATION forming part of Letters Patent No. 773,459, dated October 25, 1904.

Application filed August 15, 1904. Serial No. 220,741. (No model.)

To all whom it may concern:

Be it known that I, MARTIN L. BEISTLE, a citizen of the United States of America, residing at Ingram, in the county of Allegheny and 5 State of Pennsylvania, have invented certain new and useful Improvements in Trolleys, of which the following is a specification, reference being had therein to the accompanying drawings.

10 This invention has relation to trolleys, and more particularly to the harps thereof; and the object of this invention is to provide a novel form of harp in which the trolley-wheel is adapted to be mounted, and I have employed 15 novel means in connection with my improved hub whereby the same will at all times be retained in engagement with the trolley-wire.

It is a well-known fact that considerable trouble has been experienced on account of the trolley-wheels leaving the trolley-wire when the 20 cars or vehicles are passing around a curve when irregularities in the wire are encountered, and when constructions such as the overhead work under bridges and the guide-wires 25 obstruct the path of travel of the trolley-wheel the same have a tendency to leave or "fly off" the wire, and to overcome this discrepancy I have provided a swiveled harp, said harp having pivoted arms in which the trolley-wheel 30 is journaled, and I form said arms whereby they will extend upwardly at each side of the wire and guide the movement of the wheel upon said wire should the same become disengaged, and in connection with said arms and 35 harp I employ springs to normally hold the trolley-wheel in engagement with the wire. The springs which I employ are an auxiliary adjunct to the ordinary springs employed in connection with the trolley-pole at the base 40 thereof and carried by the top of the street-car.

The construction briefly described above will be hereinafter more fully described and then specifically pointed out in the claims, and 45 referring to the drawings accompanying this application like numerals of reference indicate similar parts throughout the several views, in which—

Figure 1 is a side elevation of a trolley-pole 50 having my improved harp mounted thereon.

Fig. 2 is a side elevation view of my improved harp, partly in section. Fig. 3 is an end view thereof. Fig. 4 is a top plan view of my improved harp.

To put my invention into practice, I construct my improved harp and its appurtenant parts upon the trolley-poles commonly used, and in Fig. 1 of the drawings I have illustrated one of these poles, which is designated by the reference-numeral 1. This pole is pivotally 55 mounted, as indicated at 2, to the top 3 of a car, and said pole is forced upwardly and controlled by the trolley tension-controller or device, as indicated by the reference-numeral 4, this trolley controller or device being of the 60 ordinary and well-known construction commonly used. To the upper end of the pole 1 I swivel my improved harp 5, and to accomplish this I provide a screw-threaded contracted end 6 at the top of the trolley and upon 65 the end of the harp 5 provide a headed pin 7, which is retained upon the end of the trolley 1 by a screw-threaded sleeve 8, this construction permitting the harp to rotate upon the end of the trolley, the form of the swivel 70 shown being of a well known and defined nature, and I do not care to limit myself to this specific form of swiveling the harp, but may employ any desired construction whereby the 75 same result will be accomplished. 80

The harp proper consists of a curved bar which in its lower end has formed an aperture 9, and through said aperture passes a pin 10, which carries on its outer ends the upwardly-extending arms 11 11, the upper ends 85 of which are curved and bent outwardly, as indicated at 12 12, these arms being adapted to extend parallel to the trolley-wire 14, as clearly illustrated in Fig. 1 of the drawings. The end of the harp 5 is formed with a depending lug 15, which is provided by cutting away the end of the curved bar comprising the harp, as designated at 16. Near the ends 90 of the arms 11 11 I mount a pin 17 between said arms, this pin being adapted to engage the depending lug 15, which acts as a stop and prevents a downward movement of the arms 11 11. The harp is provided with apertures 18 18, in which the end of a trolley-rope 19 95 may be secured. Between the arms 11 11 100

and intermediate the ends of said arms is journaled a pin 20, and upon this pin is mounted a journal-wheel 21, said wheel being of the ordinary form now commonly used. The bar 5 comprising the harp 5 is provided with pins 22 22, to which are connected the ends of springs 23 23, the other ends of the springs being connected to pins 24 24, carried upon the outer side of the arms 11 11.

10 When the trolley pole and harp are in the position shown in Fig. 1, the springs 23 23 are adapted to normally hold the trolley-wheel in engagement with the trolley-wire, and should any obstruction interfere with the travel of 15 said wheel, causing the same to become disengaged from the wire, the springs 23 23 will return the wheel to engagement with the wire 14, this return movement being facilitated by the upper curved ends of the arms 11 11, which 20 serve as guide-arms to place the trolley-wheel back in engagement with the wire. By employing the auxiliary springs 23 23 in conjunction with the pivoted arms 11 11 I have provided novel means whereby should the tension-controller 4 not return the trolley-pole 25 with as great a rapidity as required to immediately place the trolley-wheel upon the wire the springs 23 23 will move the arms 11 11 upwardly until the wheel has become engaged 30 with the trolley-wire. Should an obstruction be encountered by the wheel, the depending lug 15, formed by the end of the harp, will prevent the obstruction from forcing the arms downwardly past said lugs, and should the pin 17, 35 carried by said arms, engage said lug and the obstruction continue to press said arms downwardly the trolley-pole 1, which is pivoted at 2, will receive and permit the obstruction to pass, at which time the tension device 4, in 40 conjunction with the springs 23, will immediately and with considerable rapidity return the trolley-wheel to its normal position.

The reference-numeral 25 indicates a set-screw which is employed in connection with 45 the swiveled connection of the harp with the trolley-pole 1, this set-screw being used to provide a fixed connection when it is desired, whereby it will be impossible for the harp to swing upon the pole.

I wish it to be understood that I do not care 50 to confine myself to the use of the two springs shown in Fig. 2 of the drawings, but may employ one spring of a sufficient tension, which may have its one end mounted between the arms, while its other end is secured upon the 55 top of the harp at a point similar to the pins 22 22 heretofore described, and I do not care to limit myself to the specific shape or contour of the arms 11 11, but may so form the same in connection with the trolley-pole 1 60 whereby the results above enumerated will be realized and a construction provided which will be advantageous to the general operation of the trolley-pole.

Having fully described my invention, what 65 I claim, and desire to secure by Letters Patent, is—

1. The combination with a trolley-pole, of a harp swiveled thereon, said harp comprising a curved bar, arms pivoted to said bar, a trolley-wheel journaled between said arms, means 70 for limiting the downward movement of said arms, and means for normally holding said arms in an elevated position.

2. The combination with a trolley-pole, of 75 a harp swiveled to the upper end of said pole, arms pivotally connected to said harp, the upper ends of said arms being bent outwardly and extending above the trolley-wire, a trolley-wheel journaled between said arms, means 80 for limiting the downward movement of said arms, and means whereby said trolley-wheel will be normally held in engagement with said wire.

3. The combination with a trolley-pole, of 85 a curved bar swiveled upon the outer end of said trolley-pole, curved arms pivotally connected to the lower end of said bar, the upper ends of said arms being bent outwardly, a trolley-wheel journaled between said arms, means for 90 limiting the downward movement of said arms, and means for normally elevating said arms.

In testimony whereof I affix my signature in the presence of two witnesses.

MARTIN L. BEISTLE.
